Albert M. Freeman BY
ATTORNEY.

UNITED STATES PATENT OFFICE.

SAMUEL K. PEEL AND WILLIAM ENGLUND, OF SIOUX FALLS, SOUTH DAKOTA.

DECOY DUCK.

Application filed September 19, 1921. Serial No. 501,781.

To all whom it may concern:

Be it known that SAMUEL K. PEEL and WILLIAM ENGLUND, citizens of the United States, residing at Sioux Falls, in the county 5 of Minnehaha and State of South Dakota, have invented certain new and useful Improvements in Decoy Ducks, of which the following is a specification.

This invention relates to certain new and 10 useful improvements in decoy ducks, and the primary object thereof is to provide a device of this kind which can be easily and quickly taken apart and otherwise assembled so as to enable compact packing of the 15 device.

A further object of the invention is to provide means for enabling the body of the duck to be easily and quickly applied to and removed from the float, and to also provide improved ballast means which is foldable to lie against the float.

A still further object of the invention is to provide a structure of this kind which is of simple construction, and which can be 25 economically produced.

Further and other objects will be later set forth and manifested in the course of the following description.

In the drawings:

30 Figure 1, is a side elevation of the invention partly broken away and in section.

Figure 2, is a section on line 2—2 of Figure 1, and

Figure 3, is a top plan view.

35 In proceeding in accordance with the present invention a preferably flat wooden float or base 1 is employed, which as shown in Figure 3 of the drawings is shaped to represent the lower part of the body of a duck 40 when the latter is in swimming position. A preferably tin strip 2 is secured by nails or other suitable fastenings 3 to the upper face of the base 1, the strip being preferably offset as shown in Figure 2, or otherwise 45 secured so that the part between the fastenings is loose and can be readily moved up from the base 1 to accommodate a right angular flange 4 formed on a preferably tin member 5, the latter, as shown in Figure

50 1 being shaped to represent the head and tail and the upper body portion of the duck. The under face of the base 1 is formed with a pair of bored holes 6 across which pins 7 are projected, the pins being driven into the 55 base 1 from the outer side edges thereof as shown in Figure 2. A U-shaped wire 8 is

bent to form eyes 9 at its free ends, which eyes are secured about the pins 7. A weight such as a piece of lead or other ballast 10, is secured to the lower free part of the wire 60 member 8. The ballast serves to hold the decoy upright in the water, preventing the latter from tipping over due to either the presence of wind or the movement of the water.

65 The base 1 and the attaching strip 2 as well as the body member 5 are painted to represent a duck on all the exposed parts thereof above the water line.

70 From the foregoing it will be seen that the device can be economically produced and assembled, the latter involving boring of the holes 6, followed by placement of the eyes 9 in the holes, after which the pins 7 are driven through the eyes and into the 75 base 1 so as to extend across the bored holes 6. The attaching member 2 is simply nailed at its ends to the upper face of the base 1, while the body part 9 can be produced by cutting or stamping same out of tin or other 80 metal, followed by bending of the flange 4. The flange 4 has a tight frictional fit between the base 1 and the strip 2, and as shown in Figure 3 the ends of the flange 4 engage between the fastenings 3, so that the 85 flange is held against movement longitudinally of the base 1.

86 The member 8 folds against the under face of the base 1 with the weight 10 disposed in part above the under face of the 90 base and in front thereof. The part 5 upon being disengaged from the strip 2 can be placed flat on the base, and the device can thus be easily stored, since it will occupy considerably less room than when the parts 95 are in the position of Figures 1 and 2. Further, the rear side walls of the hole 6 will engage the member 8 and limit rearward swinging movement of the latter as shown in Figure 1. The base may be cut-out 100 of boards or scrap pieces of boards can be utilized.

What is claimed is:

1. In a decoy duck, a base, a strip having means to secure same at its ends to the 105 upper face of the base, and a metal member shaped to simulate the head, tail and upper body part of a duck having a base flange frictionally engaged between said strip and the upper face of the base, said base flange 110 being movable sidewise into engagement with the strip and having its ends disposed

between the securing means at the ends of the strip.

2. In a decoy duck, a wood base having holes in its under face spaced from the outer sides thereof, a U-shaped wire having its ends formed with eyes which latter are disposed in the holes, pins driven into the base, and extending from the outer sides of the base inwardly thereof across the holes 10 and through the eyes, and a weight on the lower end of the wire.

3. In a decoy duck, a base having a pair of holes in its under face spaced from the side edges of the base, a wire of approximately U-form having eyes on its ends arranged in the holes, pins extending from the side edges of the base inwardly thereof across the holes and through the eyes, said eyes being formed to allow the wire to move 15 toward one end of the base and to lie against the latter and when the wire is moved in the opposite direction to abut the adjacent walls formed by the holes to limit rearward

movement of the wire, a weight on the rod, and a member simulating the head, tail and upper body part of a duck carried by the base.

4. In a decoy duck, a base, a member shaped to simulate the head, tail and upper body part of a duck and having a base flange 30 extending outwardly from a side thereof and at substantially right angles thereto, and a member secured to the upper face of the base and having a part thereof extending above the upper face of the base and formed 35 to receive and frictionally hold said base flange onto the base by sidewise movement of the base flange, and means to prevent endwise movement of the base flange when operatively connected to said part of the member.

In testimony whereof we affix our signatures.

SAMUEL K. PEEL.
WILLIAM ENGLUND.
